UNITED STATES PATENT OFFICE.

JOHN P. KAESZMANN, OF MILWAUKEE, WISCONSIN, ASSIGNOR OF ONE-HALF TO GEORGE DERFUS, OF SAME PLACE.

WASHING-MACHINE.

SPECIFICATION forming part of Letters Patent No. 358,275, dated February 22, 1887.

Application filed November 6, 1885. Serial No. 181,991. (No model.)

To all whom it may concern:

Be it known that I, JOHN P. KAESZMANN, of Milwaukee, in the county of Milwaukee, and in the State of Wisconsin, have invented 5 certain new and useful Improvements in Washing-Machines; and I do hereby declare that the following is a full, clear, and exact description thereof.

My invention relates to washing-machines; 10 and it consists in certain peculiarities of construction, as will be hereinafter described with reference to the accompanying drawings, in which—

Figure 1 represents a side elevation of my 15 invention; Fig. 2, a vertical section taken on line y y , Fig. 1; Fig. 3, a partial top plan view showing the ratchet mechanism in detail; Fig. 4, a vertical transverse section of the complete machine applied as a washer; Fig. 5, a top 20 plan view of the same with the cover removed; Fig. 6, a detail view of the steam-pipe coupling.

A' are standards arranged at right angles to each other and braced apart by a single 25 casting having right-angular arms a a' , adapted to be secured to said standards. The several standards have their respective inner portions, b b' , upwardly extended and suitably united to the right-angular wings c c' of a head-piece, 30 B, centrally perforated to form a bearing for a vertical shaft, D. These upwardly-extended portions of the standards are further secured to and braced apart by a right-angular casting, C, located below the head-piece B, and 35 also centrally perforated to form a bearing for the shaft D.

The standards A are provided with bearings d for horizontal shafts E E', having secured to their inner ends disks F F', united 40 by a coupling, G, which latter passes through a slot, e, in a plate, f, secured to the lower end of the vertical shaft D, said plate being provided with guides g, designed to operate upon the upwardly-extended inner portions b' of the standards A'.

The horizontal shaft E is provided at its outer end with a fly-wheel, H, and the shaft E', at its outer end, is provided with a pinion, h, adapted to mesh with a gear-wheel, h', journaled on a bearing at the upper outer end, i, of the standard supporting said shaft E', and

to this gear-wheel is secured a crank, I, by which my machine is designed to be operated; or, in place of the crank, a band-pulley or other means may be employed to communicate motion to the several operating parts. Secured to the standards supporting the shaft E' are right-angular brackets k k' , forming bearings for a traveler, K, having a central depression, l, in which operates a flanged eccentric, m, secured to said shaft.

To one end of the traveler K is pivotally secured a pawl, M, having its free end passed through a loop, n, on the inner bracket, k', this pawl being held in operative position by said loop and a spring, o, this latter being secured at one end to the traveler K and at the other to the forward portion of said pawl. To the inner bracket, k', is secured one end of a spring-stop, N, the free end of said stop and that of the pawl M being arranged to engage the teeth of an annular rack, O, upon the under side of the base Q for a tank, Q', said base having a bearing on the outer upper ends of the standards A A', the tank being designed as a receptacle for clothes when the machine is employed as a washer. The base Q of this tank is preferably composed of wood and provided with a flanged ring, p, designed to engage a similar ring, q, resting upon the standards A 75 A', and adapted to be secured to the upwardly-projecting portions b b' of said standards. This tank bottom and base are also provided with a central opening, from which projects a casing, r, adapted to inclose the upwardly-extended portions of the standards, and surrounding this casing is a shell, r', provided at its bottom with a series of perforations, r''.

Adapted to fit between the casing r and the shell r' is a cap-piece, R, provided with slots, s and a removable cover, s', said slots being designed to receive a horizontal bar, S, having its ends turned down and bifurcated, as shown at t, adapted to have fastened thereto suitable blocks, t', to form pounders for the clothes. The central portion of the horizontal bar S is provided with a grooved sleeve, u, designed to fit upon the upper end of the vertical shaft D, the latter having lugs u', designed to engage the grooves in said sleeve. The vertical shaft is also provided with a collar, u'', between which and the bar S is inter-

posed a spring, v , and above the sleeve u of said bar is a spring, v' , the tension of these springs being regulated by means of a nut, v^2 , operating on the screw-threaded upper end of the vertical shaft D . After the arm S is placed in position with relation to the slots in the cap-piece R that portion of these slots above the arm is closed by means of strips s^2 , that depend from the removable cover S' of said cap-piece, thereby, when the cover s' is in place, entirely excluding the water in the tank Q' from coming into contact with the operating mechanism of the machine, as all water that may splash against or collect on the cap-piece will escape down the exterior thereof, between it and the shell r' , and when the water is drawn off from the tank all that remains between this shell and the casing r will run into said tank through the perforations r^2 at the lower portion of said shell.

The tank Q' is provided at its upper portion with a flanged seat, w , for a removable cover, T , said seat having a series of perforations, w' , through which the drip from the cover runs back into the tank. Designed to rest upon the bottom of the tank is a seat for the clothes, said seat being preferably composed of a series of radial strips, w^2 , having secured to their upper faces a series of concentric rings, w^3 , and to their under faces suitable springs, w^4 , this construction acting as a cushion for the clothes when acted upon by the pounders t' , and at the same time permitting the water to have a free circulation throughout said clothes during the operation of washing. The pipe for introducing steam into the tank is composed of sections U , united by swivel-couplings V , said couplings being each composed of an outer shell, x , having an internal flange, x' , at its lower end to receive the shoulder z' of a tube, z , this latter part being provided with a collar, z^2 , and constructed at its lower extremity to receive one of the pipe-sections. The lower section of the exterior steam-pipe, composed of parts U V , connects with a circular pipe, U' , located within the tank Q' , this circular pipe being provided with a series of perforations, so that the steam may escape and keep the water in said tank at a high state of temperature.

This style of washer is designed for large laundries; but in machines designed for family use the apparatus for introducing steam into the tank may be omitted.

To the upper end of the shell x is secured a sleeve, z^2 , into which is projected the upper extremity of the tube z , said sleeve being constructed at its upper terminus to receive a pipe-section. Interposed between the shell x and the collar z^2 of the tube z is a spring, z^4 , which acts to retain the flange of said shell and the shoulder of the tube in close contact to form a tight joint. This construction and arrangement of the parts forming the coupling V is fully illustrated in detail, Fig. 7.

In the operation of my invention, the several parts being in their relative positions and

motion communicated to the shafts E E' , the disks F F' on the inner ends of these shafts will be rotated and their coupling G moved back and forth in the slot e of the plate f , thus vertically operating the shaft D . As this shaft is vertically operated it carries with it the arm S , resting in the slots s of the cap-piece R , thereby causing the pounder-blocks t' to act upon the clothes which are placed in the tank Q' on the cushioned seat formed by the radial strips w^2 , concentric rings w^3 , and springs w^4 . The eccentric m is also operated by the revolution of the shaft E' to actuate the traveler K , thereby causing the pawl M to operate against the teeth of the annular rack O to rotate the tank Q' , the spring-stop N also engaging said teeth to prevent any backward movement of said tank when the pawl is being carried back from one to engage the next succeeding tooth. By the peculiar coupling connecting the several sections U of the steam-pipe this latter forms no barrier to the rotation of the tank Q' , but is carried with said tank during the operation of the machine, and when it is desired to remove the cover T the upper section of the pipe is swung around out of the way, it being intended that this section shall be connected to a main supply-pipe or boiler by a steam-hose.

Having thus fully described my invention, what I claim as new, and desire to secure by Letters Patent, is—

1. A supporting-frame consisting of a series of suitably-braced standards having upwardly-extended inner portions and provided with a flanged ring, in combination with horizontal shafts journaled in bearings on said standards, and each provided at its inner end with a disk, a coupling uniting these disks, a slotted plate operatively secured to said coupling, and a vertical shaft connected to this slotted plate, a horizontal arm removably secured to said vertical shaft and provided with turned-down ends carrying blocks, a suitable tank having a central casing and opening, its base provided with an annular rack, and a flanged ring engaging the one on the supporting-frame, a pawl and stop mechanism suitably connected to said frame to engage the annular rack upon the tank-base, and an eccentric on one of the horizontal shafts, substantially as and for the purpose set forth.

2. A supporting-frame consisting of suitably-braced standards having upwardly-extended inner portions united by a right-angular centrally-perforated casting, and a centrally-perforated head-piece having right-angular wings, a vertical shaft having a bearing in said casting and head-piece and secured at its lower end to a slotted plate, and a horizontal arm removably connected to this vertical shaft and provided with turned-down ends carrying blocks, in combination with a tank having a central casing, a surrounding shell for said casing perforated at its bottom, and a perforated flanged seat for the tank-cover, a cap-piece slotted to receive the horizontal arm and

adapted to fit between the central casing and shell, said cap-piece being provided with a removable cover, a cushion to fit within the tank and composed of radial strips having upon 5 their upper faces concentric rings and upon their under faces suitable springs, a coupling operatively secured to the slotted plate and united to revolving disks, a pawl and stop mechanism, and an annular rack upon the 10 tank-base arranged to have its teeth in engagement with said mechanism, substantially as and for the purpose set forth.

3. The vertical shaft D, having a collar, u^2 , and lugs u' at its upper end and a slotted plate, 15 f , at its lower end, in combination with a horizontal arm, S, having grooved sleeve u fitted to the vertical shaft and turned down at its ends to receive blocks, springs $v v'$, and bearings B C, a suitable tank, Q', having a central 20 opening and a casing, r , and upon its bottom an annular rack, O, shafts E E', carrying disks F F', united by a coupling, e, operating in the slot of the plate f , an eccentric on the shaft E', a pawl and stop mechanism operatively engaging 25 said eccentric and the annular rack on the tank-base, and a suitable supporting-frame for said tank and operating mechanism, substantially as and for the purpose set forth.

4. The traveler K, having a depression, l , 30 and operatively secured to brackets $k k'$ on a supporting-frame, a spring-pawl pivotally secured to said traveler, and a spring-stop, N, connected to one of the brackets, k' , in combination with an eccentric upon a horizontal 35 shaft, E, operative in the depression of said traveler, a suitable tank provided upon its base with an annular rack, O, to engage the spring pawl and stop, and a vertical shaft, D, having suitable bearings and provided with a removable 40 horizontal arm carrying blocks and operatively connected to a disk, F, on said horizontal shaft, substantially as and for the purpose set forth.

5. The tank Q', rotated upon a suitable supporting-frame and provided with an interior 45 perforated endless steam-pipe, U', and an exterior steam-pipe composed of a series of sections, U, united by swivel-couplings V, substantially as set forth.

6. In combination, the tank Q', rotated upon 50 a suitable supporting-frame and provided with an interior endless steam-pipe having perforations therein, the exterior steam-pipe sections U, and the swivel-couplings V, each of the latter composed of an outer shell, x , having an 55 internal flange, x' , a tube, z , provided with a shoulder, z' , and collar z'' , a sleeve, z''' , and a spring, z'''' , exteriorly arranged on the tube z between said flange and collar, substantially as and for the purpose set forth. 60

7. The supporting-frame consisting of standards A A', having upwardly-extended inner portions, $b b'$, a single casting having arms $a a'$, the head-piece B, and casting C, in combination with the vertically-operating shaft D, horizontal arm S, having bifurcated turned-down ends t , carrying blocks, slotted plate f , coupling e, and revolving disks upon the inner ends of horizontal shafts E E', operating in bearings $d d'$, a flanged eccentric, m , and pinion h 65 on shaft E', a traveler, K, having a depression, l , for the eccentric m , the spring-pawl M, pivoted to said traveler, the spring-stop N, and brackets $k k'$, secured to one of the standards A, the flanged ring q , supported by the standards, a suitable tank having a central opening and central casing, r , and provided upon its base with a flanged ring, p , and an annular rack, O, a fly-wheel, H, and a gear-wheel, h' , driven by a crank, I, all arranged to operate 70 substantially as described. 75

8. The detachable arm S, having a grooved sleeve, u , and turned-down ends t , carrying blocks, in combination with a vertical operating-shaft provided with lugs to engage said 85 sleeve, and a rotating tank supported upon a suitable frame constructed to carry the operative mechanism for driving said shaft and tank, substantially as and for the purpose set forth. 90

In testimony that I claim the foregoing I have hereunto set my hand, at Milwaukee, in the county of Milwaukee and State of Wisconsin, in the presence of two witnesses.

JOHN P. KAESZMANN.
